United States Patent Office

Des. 206,108
Patented Oct. 25, 1966

206,108

LOG TURNER OR SIMILAR ARTICLE

Jesse W. Drew, 113 Linkhorn Drive, Virginia Beach, Va.

Filed Nov. 12, 1965, Ser. No. 88,077

Term of patent 14 years

(Cl. D81—24)

FIGURE 1 is a perspective view of a log turner or similar article of the present invention;

I claim:

The ornamental design for a log turner or similar article, as shown and described.
